FIG. 3.

Inventor
Frederick G. Mitchell

By his Attorney
Israel Benjamins.

UNITED STATES PATENT OFFICE.

FREDERICK G. MITCHELL, OF RIDGEFIELD PARK, NEW JERSEY.

AUTOMATIC CUT-OFF SWITCH FOR RADIO RECEIVING SETS.

Application filed December 6, 1924. Serial No. 754,350.

To all whom it may concern:

Be it known that I, FREDERICK G. MITCHELL, a citizen of the United States, residing at Ridgefield Park, in the county of Bergen and State of New Jersey, have invented a new and useful Automatic Cut-Off Switch for Radio Receiving Sets, of which the following is a specification.

My invention consists in the novel features hereinafter more fully described.

One of the objects of my improvement is automatically to disconnect the electric tube circuits of radio receiving sets at a predetermined time, thereby preventing unnecessary using up of the tubes and batteries when the operator forgets to open the switch in time.

Another object of my improvement is to enable the operator to use my cut off switch also for disconnecting the circuit by hand at any desired moment.

A further object of my improvement is to have my automatic cut off switch simple, durable and inexpensive.

Other objects and advantages of my improvement will hereinafter appear.

I attain these objects by the automatic cut off switch, one form of which is illustrated in the drawings or by any mechanical equivalent or obvious modification of the same.

In the drawings Fig. 1 is a section on the line 1—1 of Fig. 2, and showing sundry parts in elevation.

Fig. 2 is a view partly in section on the line 2—2 of Fig. 1, omitting the clockwork mechanism and casing thereof.

Fig. 3 is a part elevation showing the handwheel, the pointer and the dial of my automatic cut off switch, which are herein-after more fully described.

Similar numerals refer to similar parts throughout the several views.

11, 12 and 13 designate respectively the rear wall, front wall and side walls of a clockwork casing; 14 is the clock spring, which is connected to the arbor 15 and pin 16, which is connected at the ends thereof to the walls 11 and 12 of the said casing.

15 The arbor 15 and gear spindles 17, 18 and 19 are pivotally connected to the said walls 11 and 12, and they have mounted thereon a train of gears 21, 22, 23, 24, 25 and 26, which are more or less diagrammatically shown in Fig. 1.

20 is an escapement or speed regulating mechanism, which with said train of gears and spring 14 forms the clockwork mechanism for actuating my automatic cut off switch. 60

The front wall 12 of the clockwork casing may be secured to the rear of the switch casing 27, which is shown as having at the left side thereof a metal plate 28, for mounting thereon the binding post 30, and at the right side thereof a plate of insulating material 29, which may be secured thereto in any suitable manner, for mounting thereon the binding post 31; suitable wires or conduits 51 and 52 connect the binding posts 70 to the electrical circuit, preferably of the battery A, of the radio set.

The front wall 32 of the said switch casing may be connected to the rear of the panel 33 of the radio set. 75

The forward end of the spring arbor 15 extends into the switch casing 27, as shown in Fig. 1, and it has connected thereto the disc 34, which has secured thereto at the periphery thereof the radial pin 38. 80

A switch disc 35 is detachably engaged by the arbor disc 34 by means of a rearwardly extending pin 39, which is secured to said switch disc 35 at right angles thereto, which pin is normally in contact with the pin 38, as shown, and is caused by said pin 38 to turn the disc 35 in a clockwise direction, thereby forming a one way clutch.

The disc 35 is carried by a yoke 36, which has two pins 37 extending rearwardly thereof into suitable openings in the front of said disc 35. 90

The yoke 36 is secured to a spindle 45, which passes through the front wall 32 of the casing 27 and the panel 33 and is pivotally mounted therein. 95

The forward end of the spindle 45 has connected thereto the hand wheel 46, which has thereon the hub 47, and it may be notched or knurled on the periphery thereof. 100

A dial 49, having thereon division lines or insignia 50, is secured to the front of the panel 33, and an index or pointer 48 is carried by the hub 47 of the wheel 46, to indicate on said dial 49 the time as determined by said clockwork. 105

The switch disc 35 is normally in electrical connection with the binding post 31 by means of the plate spring 41, which is connected at the outer end thereof to said 110

binding post 31, as shown, and terminates at the inner end thereof in the spur 44, which is normally in sliding contact with the periphery of the disc 35, thereby completing the electrical circuit of the radio set.

To break said circuit I provide in the periphery of the disc 35 a depression 42, which has thereon a liner 43 of insulating material; when, during the rotation of the disc 35, the depression 42 in the periphery thereof is brought opposite the spur 44 on the spring 41, the radio circuit is automatically broken.

15 In this way the tubes and batteries of a radio set may be saved from being used up unnecessarily when the operator forgets to open the switch of the circuit of the A battery or of any other suitable part of a radio set.

20 To prevent the disc 35 from continuing to rotate after the circuit is broken I provide the bracket 40, which may be secured to the wall 12, to intercept the pin 39 of the disc 35 at about the same time as the circuit is disconnected, as hereinbefore described, or shortly thereafter.

25 To set the automatic cut off switch for disconnecting the circuit at any required time, the hand wheel 46 is turned counter-clockwise, thereby causing the pin 39 on the disc 35 to engage the pin 38 on the disc 34, thereby turning the latter also counter-clockwise and thereby winding up the clock 30 spring 14; the index or pointer 48 is then placed opposite any required division line 35 50 on the dial 49.

30 To work my automatic switch by hand for disconnecting the circuit at any desired moment, the handwheel 46 may be turned by hand in a clockwise direction until the hand 48 on the dial 49 will indicate that the spur 44 of the spring 41 is in the depression 42, as above described.

35 45 Many changes may be made in the details of my automatic cut off switch for radio receiving sets without departing from the main scope of my invention, and parts of my invention may be used without other parts, if desired.

40 I do not, therefore, restrict myself to the details as shown in the drawings; but I intend to include also all mechanical equivalents and reasonably obvious modifications 45 of the same within the scope of my invention.

What I claim as my invention and desire to secure by Letters Patent is:

1. In an automatic cut off switch for an electric circuit of a radio receiving set a 50 clockwork mechanism, a spring arbor therein, a driving member connected to said arbor, to rotate therewith, an engaging pin projecting from said member, a driven member, carrying a corresponding pin, to be impelled by said engaging pin, and forming therewith a one way clutch, to turn said driven member in one direction and to allow said driven member to be turned in the same direction independently of said arbor, 55 an electrical conductor, having thereon a spur, in contact with said driven member, thereby completing said circuit, and a depression in said driven member, to encounter said spur, for automatically separating 60 said conductor from said driven member, thereby breaking said circuit.

2. In an automatic cut off switch for an electric circuit of a radio receiving set a 65 clockwork mechanism, a spring arbor therein, a driving member secured to said arbor, to rotate therewith, an engaging means carried by said member, a driven member carrying a corresponding means to be impelled by said engaging means, and forming therewith a one way clutch, to turn said driven member in one direction and to allow said driven member to be turned in the same direction independently of said arbor, an electrical conductor in sliding contact with said 70 driven member, thereby completing said circuit, and a means on said driven member for automatically separating said conductor therefrom, thereby breaking said circuit.

3. In an automatic cut off switch for an 75 electric circuit of a radio receiving set a clockwork mechanism, a spring arbor therein, a driving disc secured to said arbor to be rotated thereby, an engaging means carried by said disc, a driven disc carrying a 80 corresponding means to be impelled by said engaging means, and forming therewith a one way clutch to turn said driven disc in one direction and to allow said driven disc to be turned in the same direction independently of said arbor, an electrical conductor in contact with said driven disc, thereby completing said circuit, and a means on said driven disc for automatically separating 85 said conductor therefrom, thereby breaking 90 said circuit.

FREDERICK G. MITCHELL.
